UNITED STATES PATENT OFFICE.

PHILIP A. CELANDER, OF BLOOMINGTON, ILLINOIS, ASSIGNOR TO WILLIAMS OIL-O-MATIC HEATING CORPORATION, OF BLOOMINGTON, ILLINOIS, A CORPORATION OF ILLINOIS.

DESIGN FOR A STOVE.

Application filed October 27, 1928. Serial No. 28,678. Term of patent 14 years.

To all whom it may concern:

Be it known that I, PHILIP A. CELANDER, a citizen of the United States, residing at Bloomington, in the county of McLean and State of Illinois, have invented a new, original, and ornamental Design for Stoves, of which the following is a specification, reference being had to the accompanying drawing, forming part thereof.

The figure is a perspective view of the stove showing my new design.

I claim:

The ornamental design for a stove, as shown.

PHILIP A. CELANDER.
